COMBINED DOOR AND WINDOW LOCK

Anton Rappl, Buffalo, N. Y., assignor to Trico Products Corporation, Buffalo, N. Y.

Application November 14, 1941, Serial No. 419,138

3 Claims. (Cl. 70—149)

This invention relates to combined means for locking the doors and windows of vehicles.

The present invention aims to provide means whereby vehicle windows which are power operated for opening and closing may be automatically locked in any desired position of adjustment which they happen to assume, automatically upon and with the operation of locking the vehicle door. The exemplary embodiment of the present invention shown and described in detail herein contemplates the employment of fluid pressure motive means for moving a vehicle window selectively between opened and closed positions under manual control.

While certain constructions have been proposed wherein the motive means is to some extent fluid-locked to retain the window in adjusted position, such means depend upon the presence of an adequate pressure differential for maintaining selected position. After a particular period of disuse no such pressure differential may be present and accordingly the locking function of the motive means fails. In other instances self-locking pistons have been provided but the present invention renders reliance on such expedients unnecessary. According to the present invention, reliance upon fluid locking is entirely dispensed with insofar as periods when the vehicle is left with its doors locked are concerned.

A door locking system currently widely used is the one wherein an element is disposed inside of the door, usually on the garnish molding, for manipulation in conjunction with the outer door handle to render the outer door handle ineffective to open the door without the use of a key. Such a door locking system is shown and described in detail in the patent to Anderson et al. No. 2,039,873, dated May 5, 1936, and the general arrangement there shown is commercially referred to in the art as the Anderson-Bowlus lock.

The ensuing specific description and the accompanying drawing disclose a door lock which follows the general principles of the Anderson-Bowlus lock, albeit in a simplified form. The window locking system of my invention is exemplified as combined with a door locking system of this type and the novel cooperation of the several elements in providing a combined door and window locking system will appear to those skilled in the art from a perusal of the ensuing description in connection with the accompanying drawing.

While a complete and specific embodiment of the principles of the present invention is shown in the drawing and described in detail herein, it is

to be understood that my invention is not limited thereto or otherwise than as defined in the appended claims.

In the drawing:

Fig. 1 is a fragmentary elevational view of a vehicle door viewed from the interior, with the upholstery and other portions thereof removed for clearness;

Fig. 2 is a fragmentary cross sectional view in the same direction as Fig. 1 but showing the door lock portion on an enlarged scale;

Fig. 3 is a fragmentary view of the window locking latch portion of the device on an enlarged scale; and

Fig. 4 is a view similar to Fig. 3 illustrating a modified form of window locking latch mechanism.

Throughout the several figures of the drawing, like characters of reference denote like parts and the numeral 10 designates generally a vehicle door having a window 11 of the vertically sliding type. As viewed in Fig. 1, the door 10 would be hinged to the vehicle body along its right-hand edge.

As stated above, it is contemplated herein that the window 11 be raised and lowered by fluid pressure motor means and to this end there is provided a cylinder 14 pivotally secured to the door 10 as at 15 and having a piston (not shown) and a piston rod 16 pivotally connected at its outer end to the outer end of one arm 17 of a bell crank 18 whose other arm 19 carries a pin 20 at its outer end for engagement in a horizontal slot which may be formed by a bracket 21 secured against and cooperating with the under side of a lower framing element 22 of the window 11.

The bell crank 18 is pivotally secured against the door 10 as by the pivot pin 24 and movement of the piston in the cylinder 14 will obviously raise and lower the window through engagement of the pin 20 in the slot formed by the bracket 21.

A source of fluid differential pressure is indicated in dot-and-dash lines at 28 and manual control valves 29 and 30 may be selectively manipulated to divert the fluid differential pressure into either end of the cylinder 14 through the pair of branch conduits 32 and 33 leading, respectively, thereto.

Reference will now be had to the door locking means per se, following which the relationship between the door locking means and the power operated adjusting means and the locking means for the window will be set forth.

The numeral 38 designates a locking bolt which

is mounted for sliding movement in a guide 39 associated rigidly with the door 10. The left end of the bolt 38, as viewed in Fig. 2, enters a suitable bolt opening formed in the door jamb 40 and the bolt 38 may be biased to a locked position by means of a coil compression spring 41 bearing against the right-hand end of the bolt 38 and against a spring seat 42 carried by the panel of the door 10. The spring 41 may be supported by a guide rod 43 carried by the bolt 38.

A link 45 is pivotally secured to the outer end of an arm 46 which is fixed for coaxial rotation with an outer door handle 47. With the parts in the position shown in Fig. 2, the outer door handle is ineffective and the vehicle door is locked since pivotal opening movement of the handle, which would be clockwise as viewed in Fig. 2, would merely move the right-hand end of the link beneath an overhanging ledge 50 formed on the bolt 38.

The link 45 may, however, be pivoted upwardly to a position where its right-hand end engages against the ledge 50 and permits the bolt 38 to be moved thereby to open position by manipulation of the outer door handle. To this end a vertically extending bar 51 is disposed for guided vertical movement. The bar 51 may be guided by the guiding means 39 in cooperation with a strap 53 secured to the door 10. At its upper end the bar 51 is provided with a manual manipulating knob 54 which usually extends through a garnish molding 56 (Fig. 2) of the door window opening whereby it may readily be manipulated.

The bar 51 is adapted to be retained either in the vertical position shown in the drawing or in an upper position whereby it disposes the link 45 in position for engagement with the ledge 50 of the bolt 38 and such joint movement of the bar 51 and the link 45 is accomplished by the provision of a pin 58 carried by the bar 51 and engaging in an elongate slot 59 formed in the link 45. The slot 59 permits free longitudinal movement of the link 45 upon rotation of the arm 46 of the outer door handle 47.

For retaining the bar 51 in position for maintaining the link 45 in operative and inoperative position, respectively, a pair of detent openings 60 and 61, respectively, may be formed in the bar 51 for engagement with a spring pressed detent pin or ball 62 which may be retained in the bracket 53 in any convenient manner.

From the foregoing it will appear that the bar 51 may be raised and lowered by manipulation of the knob 54 from within the vehicle, but after the outer door handle 47 has been rendered ineffective by closure of the door with the knob 54 depressed and the link 45 in its extreme right-hand position (by holding the outer door handle 47 in corresponding position during closure of the door), other means are required for again opening the locked door from the outside. Such means may take the form of a pawl 65 guided for vertical movement in a lock barrel 66 together with a rotatable lock shaft 67 journaled in the barrel 66 and having an eccentric pin 68 for engagement in a horizontal groove 69 in the pawl 65.

Rotation of the shaft 67 can be accomplished only by use of a proper key inserted in the keyhole at the outer side of the lock barrel 66 and such rotation raises the pawl 65 against a flange 70 formed on a rigid lateral extension 71 of the bar 51.

It will be noted that an ordinary slamming of

the door with the knob 54 depressed, but without the intention of locking the door, results in automatically lifting the knob 54 to insure against accidental locking. This results from engagement of a cam face 72 on the bolt 38 which engages against a portion of the link 45 and raises the latter upon movement of the bolt to the right during the door closing operation, the bolt being so moved by camming against the door jamb 40. It is for this reason that premeditated locking requires holding the outer door handle 47 in the position to which it is normally moved to open the door, while the door is being closed to lock the same.

For opening the door 10 from the inside of the vehicle, an inner door handle 73 is provided and an arm 74 fixed for rotation therewith engages at its outer end a link 75 which extends to engagement with the bolt 38. The end of the link 75 adjacent the bolt 38 carries a pin 76 which engages in slot 77 formed in the bolt 38. As will be clear from the foregoing, counterclockwise rotation of the handle 73 as viewed in Fig. 1 will withdraw the bolt 38 from the bolt opening in the door jamb 40, while withdrawal of the bolt 38 from its jamb opening 40 by use of the outer door handle 47, does not disturb the inner door handle 73 by reason of the slot 77.

For locking the window 11 in any vertical position which it may chance to assume at the time of locking the vehicle door, a plurality of latch openings 80 are formed about a portion of the periphery of a hub 81 of the bell crank 18. A resilient latch arm 83 is pivotally mounted at one end against the door 10 and its other end is provided with a lug or latch tooth 84. Intermediate its ends the arm 83 is engaged by a lower extension 85 of the bar 51 as by means of a pair of pins 86 carried by such extension and disposed directly above and below the latch arm 83. From the foregoing it will appear that downward movement of the bar 51 to render the outer door handle ineffective automatically disposes the latch portion 84 of the arm 83 against the hub 81 of the bell crank 18. If the latch 84 is in registry with a notch 80 of the hub 81, it will enter such notch and lock the window effectively against opening or closing movement.

If the latch 84 does not register with an opening directly, the resilient arm 83 will flex and retain the latch 84 against the hub 81 for entrance into a notch 80 upon any subsequent fractional rotation of the bell crank 18. In a modified form of notch illustrated in Fig. 4 a hub 81' is shown as having ratchet teeth whereby the window is locked only against opening movement thereof. In such case the lug or latch tooth 84' of the latch arm 83' will be correspondingly modified.

What is claimed is:

1. A vehicle door having a window movable to and from a closed position, a latch for the door, means at the outer side of the door and connectible with said latch for actuating the latch to unlatched position, means at the inner side of the door for connecting and disconnecting the latch actuating means, said means including a manually operable member, means for locking the window, and means operable by said manually operable member to render said window locking means operative by and upon latch disconnecting movement of said member.

2. A vehicle door having a window movable to and from a closed position, means for locking said window in various positions, manual means at the interior of the door movable to render the window

locking means effective, a latch for the door and means biasing said latch to latching position, handle means for opening said latch, and means operable by and from said handle means for rendering said window locking means ineffective by and during manual latch-opening movement of the handle means.

3. A vehicle door having a window movable to and from a closed position, means for locking said window in various positions, manual means at the

interior of the door movable to render the window locking means effective, a latch for the door and means biasing said latch to latching position, handle means for opening said latch and key-controlled means accessible externally of the door for rendering said window locking means ineffective automatically upon door unlocking operation by said key-controlled means.
